CLAIM

The ornamental design for a wire bracelet, as shown and described.

DESCRIPTION

FIG. 1 is a developed plan view of the top of a wire bracelet, showing my new design.

FIG. 2 is a side elevational view of the wire bracelet as shown in FIG. 1.

FIG. 3 is a side elevational view of the wire bracelet in curved position.

FIG. 4 is a side elevational view of FIG. 3.
